(57) **CLAIM**

The ornamental design for a keypad escutcheon, as shown and described.

DESCRIPTION

FIG. 1 is a front view of a mortise lock keypad escutcheon according to the present invention.

FIG. 2 is a right side view of a mortise lock keypad escutcheon according to the present invention, the left side being substantially identical.

FIG. 3 is a back view of a mortise lock keypad escutcheon according to the present invention.

FIG. 4 is a top view of a mortise lock keypad escutcheon according to the present invention.

FIG. 5 is a bottom view of a mortise lock keypad escutcheon according to the present invention.

FIG. 6 is a front view of a cylindrical lock keypad escutcheon according to the present invention.

FIG. 7 is a right side view of a cylindrical lock keypad escutcheon according to the present invention, the left side being substantially identical.

FIG. 8 is a back view of a cylindrical lock keypad escutcheon according to the present invention.

FIG. 9 is a top view of a cylindrical lock keypad escutcheon according to the present invention.

FIG. 10 is a bottom view of a cylindrical lock keypad escutcheon according to the present invention.

FIG. 11 is a front view of an exit device keypad escutcheon according to the present invention.

FIG. 12 is a right side view of an exit device keypad escutcheon according to the present invention, the left side being substantially identical.

FIG. 13 is a back view of an exit device keypad escutcheon according to the present invention.

FIG. 14 is a top view of an exit device keypad escutcheon according to the present invention.

FIG. 15 is a bottom view of an exit device keypad escutcheon according to the present invention.

FIG. 16 is a front view of a mortise replacement lock keypad escutcheon according to the present invention.

FIG. 17 is a right side view of a mortise replacement lock keypad escutcheon according to the present invention, the left side being substantially identical.

FIG. 18 is a back view of a mortise replacement lock keypad escutcheon according to the present invention.

FIG. 19 is a top view of a mortise replacement lock keypad escutcheon according to the present invention; and,

FIG. 20 is a bottom view of a mortise replacement lock keypad escutcheon according to the present invention.

The broken line showing is included for the purpose of illustrating and forms no part of the claimed design.
